(57) **CLAIM**

The ornamental design for a logic module, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top view of the logic module; and,

FIG. 2 is a side view of the logic module.

1 Claim, 2 Drawing Sheets
(2 of 2 Drawing Sheet(s) Filed in Color)

FIG 1

FIG 2
